Primary Examiner — Michelle E. Wilson*Assistant Examiner* — Clease Moore, Jr.(74) Attorney, Agent, or Firm — Thomas | Horstemeyer, LLP(57) CLAIM

The ornamental design for a swimsuit, as shown and described.

DESCRIPTION

FIG. 1 is a front view of a swimsuit, showing my new design;

FIG. 2 is a rear view thereof;

FIG. 3 is a side view thereof;

FIG. 4 is a side view thereof, from a side opposite that of FIG. 3; and,

FIG. 5 is a front perspective view thereof.

The swimsuit comprises two pieces, the bottom piece having a different background color or shade than the top piece, for example, but not limited to, the bottom piece having a blue color. In an embodiment, the top piece of the swimsuit also has a panel of fabric on the interior of the chest portion with a color or shade that may match the color or shade of the bottom.
